DESIGN FOR A SHOE

Jacob Sandler, New York, N. Y.

Application May 22, 1947, Serial No. 139,205

Term of patent 7 years

(Cl. D7—7)

To all whom it may concern:

Be it known that I, Jacob Sandler, a citizen of the United States of America, residing in New York, county of New York, and State of New York, have invented a new, original, and ornamental Design for a Shoe, of which the following is a specification, reference being had to the accompanying drawing, forming part thereof.

Fig. 1 is a front perspective view of a shoe showing my new design.

Fig. 2 is a front perspective view of the opposite side of the shoe shown in Fig. 1.

I claim:

The ornamental design for a shoe, substantially as shown.

JACOB SANDLER.
